OF CHICAGO, ILLINOIS.

WATER-CLOSET.

1,117,089.

Specification of Letters Patent.

Patented Nov. 10, 1914.

Application filed April 25, 1910. Serial No. 557,347.

To all whom it may concern:

Be it known that I, WILLIAM A. RATCLIFFE, a citizen of the United States, residing at Chicago, county of Cook, State of Illinois, have invented certain new and useful Improvements in Water-Closets, of which the following is a specification.

The main objects of the present invention are to provide a water closet wherein the water for flushing the closet is supplied at the side of the closet, and not at the back or top, as in ordinary constructions; to provide a structure wherein the siphon jet can come into action before the jets of the wash-down rim; to provide a construction eliminating in large measure the gurgling sound ordinarily found in closets having a top inlet, wherein the sound arises from the splashing of water in the large air chamber forming the intake of the closet; to provide a construction relatively compact and adapted to be placed with its back directly against the wall; to provide a special arrangement of flushing valve and closet whereby the valve is placed in convenient position for operation and can deliver water to the intake of the closet substantially unmixed with air and at a level only slightly above the normal level of the water in the bowl of the closet.

A specific embodiment of this invention is shown in the accompanying drawings, wherein Figure 1 is a perspective view of the closet and its flushing valve. Fig. 2 is a sectional elevation of the closet showing in dotted lines the intake conduit located at the side of the closet and adapted to receive water from the flushing valve, and to deliver water to the siphon jet and to the hollow upper rim. Fig. 3 is a fragmentary section of the valve and the water intake showing the direct passage afforded for water from the valve to the intake.

In the construction shown, the water closet comprises a vitreous bowl 1 of ordinary shape, provided with a siphonic outlet conduit 2 of usual form. Above the bowl is a hollow rim 3 having jet openings 4 for delivering water to wash down the sides of the bowl. The channel of the hollow rim communicated with a chamber 5 located above the upper bend of the siphonic out-

let. At the inner end of the siphonic tube is a jet orifice or "siphon jet" 6, communicating with a chamber 7 of irregular shape, located between the two legs of the siphonic conduit. At the side of the closet, and integral with the bowl and its outlet conduit, is an intake conduit 9, opening at its lower end into chamber 7, and communicating at its upper end with chamber 5. Through this intake conduit, water is delivered to the siphon jet 6, and also to the jets of the hollow rim 3. The inlet 10 of the intake conduit is located in the side of the conduit, and opens laterally, and is located only slightly above the normal level of water in the bowl. Connected to the intake is a coupling or connector 11 of short length and arranged horizontally and connected at its outer end to a flushing valve 12.

The flushing valve 12 is located at the side of the water closet in position for convenient operation, and is adapted to deliver water directly through the short horizontal connector 11 into the inlet conduit 9 and substantially unmixed with air.

The flushing valve may be of the general type shown in detail in the United States patent to Brooks No. 876,518, issued January 14, 1908, though it is to be understood that the details of the valve may be varied without departing from the spirit of my invention as herein set forth and claimed.

In the construction shown, the flushing valve 12 comprises a valve-casing having at its lower end a tubular inlet 13 with a suitable turn valve 14. The valve casing also has a tubular outlet 15, to which the connector 11 is coupled. Within the valve casing and located just below the lower edge of the outlet is a transverse partition or annular ledge 16, supporting a valve-seat. Coöperating with this seat is a valve plunger or piston 17 having a head 18, coöperating with the valve-seat 16 to hold the supply of water in check until its release is desired. The piston also carries a head 19, which, when in raised position, engages at its periphery with a depending frame 20 carried at the top of the valve casing. The valve plunger can be manually depressed by a vertical push rod 21 which extends upward through a casing 22, and terminates

in a button or knob 23. Within the casing 22 are the elements for timing the operation of the valve, but these may vary in detail, and need not be described here.

5 The construction shown is somewhat shorter from front to back than many siphon jet closets, and has the advantage that it may be placed with its back directly against the wall of the room. If, for any 10 reason, it becomes necessary to detach the flushing valve, this may be done without drawing the water-seal from the bowl. Furthermore, if for any reason the supply of water should fail, there is no danger that an 15 inadvertent opening of the flushing valve will cause water from the bowl to be siphoned back into the water mains of the house, as would be the case if the intake inlet were located below the normal water level of the 20 bowl.

The operation of the structure above described is as follows: With water pressure on the valve, and water at normal level in the bowl, the depression of the vertical push rod and the consequent unseating of the valve plunger allows water to enter the valve and to then rush across through the short horizontal connector 11 and into the intake conduit 9. The water enters the intake conduit just above the level of the water then in the conduit, and then rises through the upper leg of the conduit into the chamber 5 and into the hollow rim 3. It does this without mixing with the air initially contained in these channels. Whatever air may have been initially in the valve casing and the short connector 11 is forced forward ahead of the water and passes upward into the chamber 5 and out through rim 3. The total absence of any air trap, and the direct delivery of the water into the intake conduit just above the level of the water normally standing in the conduit eliminates in a large measure the gurgling and 45 splashing sound ordinarily experienced with other closets wherein the water is delivered to chamber 5 at its top or rear. While the water is rising into chamber 5 and expelling the air therefrom, the increased pressure starts the siphon jet 6 and begins the movement of the soil backward up the siphon conduit. The siphon jet is well in action before the wash-down jets 4 begin to deliver water to the bowl. This 50 eliminates the churning action in the bowl sometimes found in closets wherein the inlet is so positioned that the hollow rim comes into play before the siphon jet. The action of the siphon jet is practically instantaneous, and the water in the bowl begins to recede before the washing water from jets 4 has a chance to raise the water level in the bowl.

What I claim as new, and desire to secure 65 by Letters Patent of the United States is:

1. The combination of a water closet bowl, a hollow rim encircling said bowl and having jet openings for water, a siphonic outlet conduit positioned back of said bowl and there forming a water seal, a jet orifice arranged to project water upward along said conduit, an intake conduit at the side of said bowl and integral therewith, said intake conduit having an inlet in its side which opens laterally and is above the normal level 75 of water in said bowl and is below said hollow rim, said intake conduit being arranged to convey water to said hollow rim after delivery of water to said jet orifice, a flushing valve close to the side of said bowl and 80 having its main valve seat located as low, at least, as said inlet and in direct alinement therewith, and a short straight horizontal pipe connecting said valve with said intake. 85

2. The combination of a vitreous water closet having a bowl and a siphonic outlet conduit at the back thereof forming a water seal, said bowl having a hollow rim encircling said bowl with jet openings for 90 wash-down water, a supply chamber for said rim located above said siphon conduit, an intake conduit integral with said bowl and extending along the side thereof and having an outlet for delivering water upward to said supply chamber for delivery to said hollow rim, said conduit having an inlet which opens laterally at the side of said bowl slightly above the normal water level in said bowl and somewhat below the supply chamber of said rim, a flushing valve close to the side of said bowl and having a side opening in direct alinement with the inlet of said intake conduit, and a short straight horizontal connector joining said valve 95 to said intake conduit and affording a direct and straight path for water from the seat of said valve to said inlet.

3. The combination of a vitreous water closet having a bowl and a siphonic outlet conduit at the back thereof forming a water seal, said bowl having a supply chamber leading to a hollow rim encircling the bowl and provided with jet openings for water, an intake conduit integral with said 11 bowl and extending downward along said bowl at the side of said outlet conduit, a water chamber located between the legs of said siphonic conduit and communicating with said inlet conduit to receive water 11 therefrom, said water chamber having a jet opening directed upward along said siphonic conduit, said intake conduit having an inlet which opens laterally at a level slightly above the normal water level in 1 said bowl and somewhat below the supply chamber of said hollow rim, whereby said siphon jet comes into action before the jets of said hollow rim, a flushing valve close to the side of said bowl and directly in aline- 11

ment with said inlet, and a short straight horizontal connector connected with said valve and adapted to convey water horizontally and directly from the seat of said valve to said inlet without danger of entraining air.

5 In witness whereof, I have hereunto set

my hand this twenty-first day of April, A. D. 1910.

WILLIAM A. RATCLIFFE.
